SURGICAL DEVICE

Filed Jan. 13, 1937

UNITED STATES PATENT OFFICE

2,182,390

SURGICAL DEVICE

William F. Reardon, West Hartford, Conn.

Application January 13, 1937, Serial No. 120,392

10 Claims. (Cl. 128—6)

My invention relates to surgical devices. It has among its objects to provide an improved surgical device, and also to provide such an improved device especially adapted to use when examining, operating on, or treating, the area in back of the nose and above the palate. A further object of my invention is to provide an improved device whereby this area, which it has heretofore been impossible to examine save by contact with the finger, may be made visible and illuminated, and made readily accessible to needed instruments or the like, all while working through the patient's open mouth. A still further object of my invention is to provide such an improved device in which both the illuminating means and the instrument may be disposed in a variety of different positions, in such manner as markedly to extend their possible range of use, while also expediting and markedly facilitating the work of the surgeon. Other objects of my invention are to provide such an improved device having improved angularly adjustable means for moving and holding the palate out of the way while permitting the light and instrument to have access to the space above and in back of the palate, and also to provide improved light and instrument supporting and guiding means adapted to enable the light and instrument to be readily adjusted angularly or longitudinally as desired and moved through and in rear of said palate holding means. Still other objects of my invention are to provide such an improved device which may be inverted and then placed in the mouth in such position as to be adapted to use when working on the throat in the region of the larynx, and also to provide such a device wherein in all uses thereof and when obtaining the above advantages and while the device is associated with a gag adapted to open the patient's mouth through engagement with the teeth, it is possible to minimize the amount of equipment necessarily inserted in the mouth while also extending the range of possible angulation of the device. These and other objects and advantages of my improved construction will, however, hereinafter more fully appear.

In the accompanying drawing I have shown for purposes of illustration several embodiments which my invention may assume in practice.

50 In the drawing—

Figure 1 is a side elevation of the device in one operating position in the patient's mouth, a portion of the face being broken away to illustrate the disposition of the illuminating and operating means relative to the various organs;

Fig. 2 is a detail section on line 2—2 of Figure 1;

Fig. 3 is a detail view partially in section showing the connecting means for the palate or epiglottis holding ring;

Fig. 4 is a detail view similar to Figure 1 but showing the device thereof merely inverted to permit it to be used in throat work;

Fig. 5 is a view similar to Figure 4 but showing a modified detachable form of construction also adapted for use in both areas, the same in this view being shown as applied to throat work, and

Fig. 6 is a detail view of a further modified form of invertible construction.

Referring first to the form of my invention shown in Figures 1 to 3, it will be noted that the same is shown as carried upon a well known form of mouth opening gag including tooth engaging elements 1, 2 insertable between the patient's teeth and relatively adjustable to open the patient's mouth. Herein, these elements are adjustable by moving the member 1 longitudinally relative to a usual slide 3 which is connected by a usual swinging bail 4 (the shape of which is shown in dotted lines in Fig. 1) with the upper member 2, the member 1 being adjustable as desired relative to the member 2 and slide 3 by means of usual operating ratchet mechanism 5. Further, my improved device is carried in an improved manner by the movable element of this gag structure and is of an improved adjustable construction and adapted to carry an electric light, generally indicated at L, and any selected instrument, generally indicated at I, and to permit the illumination of and work in the area, generally indicated at A, in rear of the patient's nose and above the palate, all as will more fully hereinafter appear.

In my improved construction, the tooth engaging member 1 projects laterally a substantial distance beyond a carrying portion 6, herein disposed at right angles thereto, in such manner as to provide ample room for the patient's lip. Further, the portion 6 is provided on its upper end, above the member 1, with an extension 7 and the latter carries a lug 8 transversely apertured as at 9 and extending in the opposite direction from the member 1 from the opposite side of the portion 6. Herein, this lug 8 forms a swivel support for a slide guide 10 which, in turn, is provided with depending lugs 11 extending down on opposite sides of the lug 8, the parts being connected by a swiveling screw 13. Further, it will be noted that the member 10 is spaced above the upper end of the lug in such manner that

this member 10 may move freely about the screw 13 on a transverse axis without striking the extension 7. As shown, the member 10 is also provided on its top with lateral guides 14 on its opposite edges which provide between the same a guideway open at the top and adapted to receive a slide 15, herein adjustable longitudinally as desired in this guideway into and out of the patient's mouth. As shown, this slide 15 is also provided with a depending handle 16 at its outer end and on its inner end with an upstanding loop member 17, hereinafter described, while it also carries on its top, intermediate of its ends and adjacent the handle 16, an elongated light and instrument guide structure 18 having its bottom suitably fixed to the upper surface of the member 15. Here also it will be noted that suitable means are provided for holding the member 15 in any desired position of adjustment in the member 10, these means in the illustrative structure shown in Figure 1 including a spring plate 19 adapted to be inserted beneath the slide 15, and which, through frictional action, tends to hold the guide 15 in any of its several positions of adjustment.

Referring more particularly to the light and instrument guide structure 18, it will be noted that the same comprises a plurality of elongated parallel guiding sleeves 20, 21 and 22, each of which is in the form of a tube having a longitudinally extending opening in its periphery. Two of these members 20 and 21 are herein oppositely disposed, back to back, with their openings at the outer sides thereof as shown, and their bottoms connected as by soldering or brazing, to the top of the slide 15, while the member 22 has its opening in the top and is centrally supported on and fixed to the tops of the members 20, 21 between the tops thereof. Further, it will be noted that each of these members 20, 21 and 22 is of substantial length, as shown in Figure 1 and that the inside diameter of each of these members is the same. Thus, it will be evident that with the member 22 fixed to the members 20 and 21 and these latter members 20, 21 fixed to the slide 15, an elongated guideway and support is provided in which various desired arrangements of lighting means and instruments may be carried in the different members 20, 21 and 22.

For example, I have shown herein a light L having a cylindrical body 23 adapted to be slidably and rotatably received in any of these sleeves 20, 21 and 22 and also having a usual eye piece 24 and electrical connection 25 on one end and a light 26 on the other extremity, this light L being one similar to those used in examinations of the bladder and being adapted to permit lateral vision after the manner of a periscope. Further, I have shown an instrument I having a like cylindrical body 27 and herein, for example, a cutting instrument carrying a usual blade 28 on its inner end operative in the usual manner from the opposite end of the instrument, the cylindrical body 27 herein being disposed in and similarly rotatable and reciprocable in any sleeve. Thus, it will be evident that with the sleeves 20, 21, 22 disposed as described, and the bodies 23, 27 of the light L and instrument I of the same diameter, the light and instrument may be arranged in any of several different positions in the several sleeves, i. e., in the arrangement best adapted to meet the circumstances. Further, it will be evident that in any position, both the light L and the instrument I may be moved longitudinally or rotated in their sleeves as desired in

order to bring them into a more advantageous position.

Cooperating with both the light L and the instrument I is the improved ring 17 carried on the inner end of the slide 15. Herein this ring is of a substantially greater area than the member 18 including the several sleeves, the ring extending upward and slightly outwardly relatively to the lower edges of the openings in the sleeves 20 and 21 and then around and substantially above the top of the sleeve 22. Thus, ample space is provided for the insertion of the light or instrument through the ring, while still enabling the upper end of the latter to engage and pull back the palate, herein indicated at P. Accordingly, as shown in Figure 1, the light from the lamp 26 may illumine the whole area A in back of the nose, while also enabling any laterally protruding part 28 of the instrument 27 to be used as desired in this space A in rear of the ring 17.

Here attention is also directed to the fact that, while the ring 17 may be permanently connected to the front end of the guide 15, it is also preferably suitably removably connected thereto. Herein, for example, I provide a longitudinal passage 29 in the front end of the slide 15 and a communicating enlargement 30 in rear of this passage, and also provide longitudinally extending spring portions 31 on the base of the ring 17, and lateral extensions 32 on these portions 31 which are adapted to catch over the end walls of the enlargement 30 and thereby hold the ring 17 securely in position. Further, it will be understood that in practice the ring 17 may be of varying size and conformation to meet different circumstances, while still continuing to perform its functions of pulling the palate forward and permitting access through the ring to the space A in back of the palate.

In the use of my improved construction, the patient's mouth is opened in the usual manner by inserting the tips of the members 1 and 2 between the teeth and operating the ratchet mechanism 5 of the gag. After the patient's mouth has been opened to the desired degree, the member 10 is raised from the inoperative dotted line position thereof shown in Figure 1, to the full line position therein, and the slide 15, preferably with the light L thereon, is then inserted longitudinally in the member 10. The member 10 being carried on the swivel 13, it will also be evident that by manipulation of the handle 16, both the angle and longitudinal position of the slide 15 and the light L may be varied as desired, in such manner as readily to permit the ring 17 to be located below and in back of the palate. Thereupon, the angle and longitudinal position of the parts may be similarly readily changed to raise the ring 17, and the latter may also be pulled forward as desired, in such manner as to pull the palate forward, all while permitting the light and any instrument subsequently required to be inserted through the ring and below the palate into the space between the ring and the back wall of the throat. Thus, it will be evident that the entire area A may be examined and treated or operated on with facility as necessary, the construction being such that the light and instrument may be changed from one sleeve to another, while another instrument may of course also be substituted, or two may be made available at the same time whenever desired. Attention is further directed to the fact that, while holding the guide 15 by means of the handle 16, the surgeon is enabled to effect adjustments in

angularity or longitudinal position, while his other hand is free to manipulate the light or instrument as necessary, all while he looks through the eye-piece 24. Obviously, also, when the desired work has been done, the entire apparatus may be quickly removed, as by either first withdrawing the instrument and light and then depressing the inner end of the guide 15 to depress the ring 17 and permit withdrawal of the latter, or by merely depressing the guide 15 so that the ring clears the palate and then bodily withdrawing the guide 15 with the light and instrument thereon; the member 10 then dropping back outside the mouth into the dotted line position shown in Figure 1 and the whole gag then also being removable in a usual manner.

As a result of the use of my improved construction, it is made possible for the first time, so far as I am advised, to illumine, and to treat or operate upon the area in back of the nose and above the palate while this area is illumined, and accordingly to obtain results heretofore unobtainable. Further, with my improved construction, it is possible to utilize various instruments and technique in this new area such as have, in general, heretofore only been usable in kidney and bladder work. Attention is further directed to the fact that, if desired, as shown in Figure 4, the device illustrated in Figure 1 may, without change, be inverted and placed in the mouth with the member 2 in engagement with the lower teeth and the member 1 in engagement with the upper teeth and used for work in the throat. In this position of the device, it will be evident that the member 10 will be a pendent member and the guide 15 and ring 17 will depend therefrom; all while continuing to enable the described adjustment of the guide 15 as to angularity and longitudinal position and the desired longitudinal and rotary adjustment of the light L and any instrument I in the sleeves 29, 21, 22. Thus, it is possible to use the ring 17 as a holding means for the epiglottis, generally indicated at E, and to use the light and the instruments in the same general manner heretofore described, in the area B adjacent or below the epiglottis. In this connection, it will, of course, also be understood that with the ring 17 removable as described, various other forms of ring may be readily substituted for that shown, including rings of different sizes and disposed at different angles to the member 15, as adapted to meet different conditions.

In Figure 5, I have illustrated a modified construction which may be used if desired. In this construction, the members 1 and 6 and lug 7 are as previously described, but it will be noted that I have modified the member 2 and the construction at the upper end of the member 4 which constitutes the support for the member 2. More particularly, the member 2 is provided with an outwardly extending lug 33 connected by a vertical screw 34 to a lug of the member 4 to permit the member 4 to swivel relative to the upper end 35 of the screw 34. Further, it will be observed that an additional outwardly extending lug 36 is provided on the outer extremity of the lug 33 and below the latter, and that the slide guide 10 is pivotally connected to this lug 36 by a swivel screw 37 at right angles to the screw 34. Thus, obviously, it is possible to mount the member 10 on the lug 7 as heretofore described in connection with Figure 1, or, if desired, remove it from the lug 7 and mount it on the lug 36 and thereby support it for work in the throat, as previously described in connection with Figure 4.

Attention here is also directed to the fact that, in lieu of the spring holding means 19 previously described, I have herein shown a laterally disposed adjustable set screw 37' carried in the side of the member 10 and adapted to engage the side edge of the member 15 and thereby hold the latter in any desired position of longitudinal adjustment relative to the member 10.

In Figure 6, a further modified construction is shown. Therein, it will be noted that both the members 1 and 2 are of modified form and that the member 1 is arranged in a new location on the member 6 relative to the pivot for the member 10. More particularly, note that instead of the lug for member 10 being above the member 1, a lug 38 is provided on the member 6 which is so disposed that the top of the member 1 and the top of the lug 38 are disposed in the same plane while the member 10 is pivoted on this lug 38 by a screw 39. Thus, the top of the member 1 may abut directly against the bottom of the member 2, as distinguished from being necessarily spaced therefrom. Further, it will be noted that both the members 1 and 2 are provided with adjacent flat faces, and that the member 2 is provided with a thin inclined end 40, while the member 1 is also provided with a like thin, herein shorter, inclined end 41. Such a construction, in addition to enabling the two members 1 and 2 to be brought closer together than in the forms heretofore described, also enables the ends 40, 41 of the same, which have to be inserted between the teeth, to be thinner than possible in previous constructions, all in such manner as markedly to facilitate the process of inserting the device between the patient's teeth in difficult cases. In connection with this form of my invention, it will also be understood that the structure can be inverted, as described in connection with Figure 4, for throat work. Here and in connection with all forms of the members 1 and 2, as shown, it will of course also be understood that if desired the surface engaged by the patient's teeth may include a suitable rubber or fiber insert, or be "leaded", in a customary manner, in order to prevent injury to the teeth as a result of the use of the gag.

My improved construction is particularly useful in cases of deafness, wherein it is frequently important to be able to examine or treat, or to be able to operate upon, the area in back of the nose and above the palate. However, it will be evident that it may be used to advantage in the treatment of various other ailments in this area or in the throat. Attention further is directed to the fact that it is thus usable in both areas without requiring any additional mechanism, the form shown in Figures 1 and 6 being simply inverted and inserted without any change whatever, in the general manner shown in Figure 4, while the form shown in Figure 5 requires only the transposition of the member 10 which can be quickly and readily effected. Here, it will also be understood that under certain conditions when working in the throat, the ring 17 on the slide 15 may also be inverted without inverting the slide or changing the position of the guide 10. Further, under these conditions, the light L and instrument I then of course not passing through the ring, no aperture need be provided therein. These and other advantages of my improvements will, however, be clearly apparent to those skilled in the art.

While I have in this application specifically described three forms which my invention may

assume in practice, it will be understood that these forms of the same are chosen for illustrative purposes and that the invention may be modified and embodied in other forms without departing from its spirit or the scope of the appended claims.

What I claim as new and desire to secure by Letters Patent is:

1. In a surgical device, a support having a guide, a slide mounted in said guide carrying on its front end laterally extending organ engaging and positioning means having an aperture therein, instrument guiding means on said slide, and an instrument movable in said guiding means transversely of said laterally extending means and through the aperture therein.
2. In a surgical device, a support having a guide, a slide mounted in said guide carrying on its front end laterally extending organ engaging and positioning means having an aperture therein, instrument guiding means on said slide in rear of said aperture having a plurality of guideways, and a plurality of instrument and light carrying slide means selectively usable in said guideways and slidable therein transversely of said laterally extending means and through the aperture therein.
3. In a surgical device, supporting means including a supporting element, a guide pivoted on said element, a slide carried by said guide having a laterally extending apertured organ positioning member on its front end and rearwardly located guiding means, and cooperating means having a portion adjustable in said guiding means and a front end portion projectible longitudinally through the laterally extending aperture in said positioning means.
4. In a surgical device, supporting means including a supporting element, a guide pivoted on said element, a slide in said guide, laterally extending organ positioning means on the front end of said slide having an aperture extending laterally of said slide, and light and instrument guiding means carried by said slide in rear of said positioning means for directing a light and instrument through the laterally extending aperture in said positioning means.
5. In a surgical device, jaw opening mechanism including relatively movable elements, a guide pivotally mounted on one of said elements, and a slide carried by said guide having on its front end apertured organ positioning means and also having cooperating guiding means in rear of the aperture in said positioning means.
6. In a surgical device, jaw opening mechanism including relatively movable elements, a guide pivotally mounted on one of said elements, and a slide carried by said guide having on its front end apertured organ positioning means and also having cooperating guiding means in rear of the aperture in said positioning means.
7. In a surgical device, jaw opening mechanism including a frame having a fixed tooth engaging element thereon and a cooperating tooth engaging element movable relative to said fixed element, a slide receiving guide movable with said movable element, a slide mounted in said guide having laterally extended apertured organ engaging and positioning means, and an instrument carrying slide mounted in said guide in position to have an instrument carried thereby projected through said aperture, said guide having parallel guideways directing said slides for longitudinal movement relative to each other.
8. In a surgical device, jaw opening mechanism including fixed upper and movable lower tooth engaging elements and means for adjusting the lower element relative to the other, a slide receiving pivoted guide adjustable with said movable element, means for at will pivoting said guide in operative position on said fixed element, a slide on said guide having apertured organ engaging and positioning means through which instruments may be inserted, and a plurality of guides for selectively receiving lighting means and instruments projectible through said aperture.
9. In a surgical device, jaw opening mechanism including relatively movable elements, and a guide pivotally mounted on an axis fixed relative to one of said elements and adapted to receive a slide and permit insertion and angulation of the latter in a patient's mouth, said guide being pivoted on a transverse axis in rear of and below the upper surface of said element and said elements being engageable in their closed position and having oppositely disposed thin ends insertable together between the patient's teeth while said elements are thus engaged.
10. A surgical device comprising jaw opening mechanism, an apertured organ positioning means slidable thereon in a patient's mouth, means for enabling angulation of said positioning means, light and instrument guiding means carried on said positioning means in rear of the aperture therein, and lighting and operating means adjustably carried by said guiding means and projectible through said aperture.

WILLIAM F. REARDON.
